CLAMPING DEVICE FOR CLOSING A FLUID OR PASTE CONTAINER

Lennart Viktor Samuel Lundahl, Motala, Sweden

Application October 31, 1955, Serial No. 543,786

14 Claims. (Cl. 222—107)

The present invention relates to clamping devices, and more particularly to certain new and useful improvements in a manually operable self-closing clamping device for closing a collapsible mouth of a fluid or paste container and of the kind in which, in the clamping action, the mouth of the container is collapsed and urged flatly against a clamping surface on a rigid frame or support by the action of a corresponding clamping surface provided on one branch of a double-branched resilient clamping member, the latter being with its other branch mounted on said frame and having a tendency to reduce the angle of opening formed between the branches, the said other branch of the clamping member being pivotally mounted at its extreme end to a stationary portion of said frame and serving as a "driving" branch, the opposite end of this branch joining the other branch resiliently, whilst this other branch forms a "clamping" branch which is thus resiliently pivotable relative to said driving branch and which carries the said clamping surface of the clamping member.

The previously known clamping devices of the kind indicated involve certain drawbacks which it is an object of the present invention to obviate. Thus, in the known device the clamping member projects laterally from the frame at a relatively great angle to the longitudinal direction of the usually tubular container whereby, in certain cases, it may be obstructive and, when mounted on a container, it is susceptible of increasing the bulk thereof. In addition, the clamping member proper is not so simple in structure as possible, and its mounting is not satisfactory in every respect. Neither has this prior device altogether efficient means for its fastening to the container.

The present invention has for its object, inter alia, to overcome these inconveniences in respect of clamping devices of the kind indicated. Further objects and advantages will become apparent as the description herein-after proceeds.

For the object stated, according to the present invention, a manually operable self-closing clamping device for closing a collapsible mouth of a fluid or paste container comprises in combination: a substantially rigid frame having a longitudinal passage therethrough and being adapted to be removably mounted on two opposite lateral edges of said container at the region of its mouth so as to grip and encase said mouth within said passage whilst leaving its fluid exit free; a flat supporting surface for one flat side of said mouth disposed on said frame so as to face said passage; an elongated "lower" clamping surface formed in said supporting surface and extending transversely of said passage; a double-branched resilient clamping member mounted at the extreme end of one of its two branches on a stationary portion of said frame situated opposite said supporting surface relative to said passage, said clamping member extending rearwardly from said stationary frame portion and in substantially spaced parallel relation to said passage and also to the second branch of said clamping member, said

2

second branch extending forwardly from the junction of the two branches and outwardly of the first branch, a substantial front end extension of said second branch being curved inwardly past the location of mounting of the first branch so as to cause its extreme end to be directed at an obtuse angle to said mouth supporting surface, and the resiliency of said clamping member being such as to urge its branches toward each other and thus the second or outer branch with its extreme end toward said mouth supporting surface, thus reducing the angle between said two branches; an elongated "upper" clamping surface formed at the extreme end of said second clamping member branch and extending transversely thereof in co-operative relation to said "lower" clamping surface formed in said mouth supporting surface, said clamping member being adapted to collapse said mouth flatly between said upper and lower clamping surface so as to close and seal said mouth; and opening cam means adapted to cooperate with said second clamping member branch to force its said upper clamping surface away from said lower clamping surface upon manually depressing the unsupported rear end portion of said clamping member.

The invention will now be described more in detail, reference being had to the accompanying drawings which illustrate a preferred embodiment thereof in a non-limitative sense and in which:

Fig. 1 is a perspective view of the clamping device as shown separately and with a portion of the clamping member broken away in order to expose internal structure.

Fig. 2 is a side elevation of the clamping device mounted on a tubular article the mouth of which is closed and sealed by the clamping device.

Fig. 3 is a plan view of the clamping device mounted on a collapsible plastic tube or the like, but with the clamping member proper removed.

Fig. 4 is a longitudinal section through the clamping device taken along the line IV—IV in Fig. 3.

Referring now to the drawings more specifically, in the embodiment illustrated therein the clamping member 1 consists of a doubled leaf spring one, shorter, branch of which, the "driving" branch 2, is pivotally mounted on the frame 3a, 3b by mounting means formed by a depending boss 4 engaging with a slight clearance an opening 5 formed in the branch 2 near its extreme end. The clamping member 1 further comprises a longer branch 6, the "clamping" branch, which is situated outwardly of the shorter branch 2 and which joins the shorter branch through the medium of a resilient connection or junction formed in the present instance by the bend 7 in the leaf spring. The clamping member 1 is mounted on the frame in such a manner that its branches extend substantially in spaced parallel relation to that portion of the frame which forms the support for the mouth portion or neck 11 of the tubular article 12 which may be made of a plastic material and may be formed of tubing having cut-in shoulder portions suitably welded together at their edges 24. Thus, the location of the pivotal mounting 4, 5 of the driving branch 2 is disposed between the tubular article 12 and the clamping branch 6. The extended free end portion 13 of the clamping branch 6 is bent inwardly past the pivotal mounting location 4, 5 of the clamping member 1 so that, during the pivotal motion of the clamping member, the clamping surface 9 provided on the extreme end of said extension will move substantially transversely relative to the longitudinal direction of the tubular article. The frame 3a, 3b is further provided with an opening cam 15 which is adapted to co-operate with the clamping branch 6 in order to force its clamping surface 9 away from the lower clamping surface 8 provided on

the base 3a when the unsupported rear end portion 7 of the clamping member 1 is being depressed manually.

The two branches 2, 6 of the clamping member 1 are substantially rectilinear in shape along a distance of the order of magnitude of the length of the inner clamping member branch 2, as considered from the junction 7 of the two branches, and the latter form between them a small acute angle. During the opening movement of the device it is arranged that said opening cam 15 slidingly engages the non-curved portion 16 of the outermost branch 6 of the clamping member 1. The opening cam 15 is formed by a transversely extending outer edge of a prismatic bridge-like element 14 which extends transversely through the hollow outer portion 3b of the frame. This bridge 14 forming the cam 15 traverses the opening formed between the two branches 2, 6 of the clamping member. The inner or driving branch 2 of the clamping member 1 is provided near its extreme end with said opening 5 by which the clamping member 1 is engaged on, and thus pivotally mounted on, said boss 4 which projects inwardly toward the longitudinal passage 10 extending through the frame, the boss 4 thus depending from the flat inner surface of said bridge 14.

The frame of the clamping device is formed by two separate mating members, viz. an "upper" member 3b and a base member 3a, the latter member forming the supporting surface for the mouth portion 11 of the tubular article 12, which surface is formed, as hereinbefore described, with the clamping surface 8. The two frame members 3a and 3b are interconnectable whilst gripping and clamping flatly between them the opposite lateral edges 24 of the tubular article 12. The upper frame member 3b comprises two opposite lateral wall portions 17 which are rigidly interconnected by the camming bridge 14 extending transversely therebetween. The two mating members 3a and 3b of the frame are formed with complementary interengagement and locating elements in the form of complementary shaped projections or shoulders 18, 19 and recesses 20, 21 for releasably interconnecting and retaining the frame members, and the latter are provided, in addition, with rearwardly and outwardly directed clamping members 22, 23 cooperating for clamping the frame about the opposite lateral edges 24 of the fluid or paste container 12. Further, in the regions of the projections 18, 19 and recesses 20, 21 the frame members 3a, 3b are slightly resilient so as to enable the frame members to be slightly deformed preparatory to their being snapped into engagement with each other, causing the clamping elements 22, 23 automatically to clamp between them the edges 24 of the tubular article 12. The cooperating clamping elements 22, 23 of the frame members 3b, 3a are formed with corresponding shallow recesses 25 and round-faced projections or bosses 26, which elements serve for locating the opposite lateral edges of the container 12 when disposed between the cooperating clamping elements 22, 23. Preferably, the two frame members consist of separate moldings of a plastic material which affords the adequate resiliency just referred to, each such molding being formed as one single unitary structure integrally with said interengagement and locating elements and with the cooperating clamping elements.

The clamping device according to the present invention is of particular importance where a manually operable sealing and closing device for containers 12 of soft plastic material, such as collapsible fluid or paste tubes, is required, and where the clamping device should be readily and simply manufactured, unobstructive and non-bulky and nevertheless exert a perfect closing and sealing action, as well as it should be easy and quick in operation. When the device is mounted on, for instance, a collapsible plastic tube 12 filled with a liquid or paste, it is an easy matter to open the clamping device into the position shown in Fig. 4 by slightly depressing the clamping member 1 by a thumb-pressure exerted on the limb or branch

6, and to pour an adequate amount of the liquid, paste or the like from the tube 12 through the neck 11 thereof. During this opening movement the clamping branch 6, 13 is being forced outwardly by the opening cam 15. Upon releasing the clamping member the latter will be relieved of its resilient force causing the clamping branch to return to its closing position as shown in Figs. 1 and 2, in which position its clamping surface urges the tube neck 11 flatly against the corresponding clamping surface of the base 3a.

The invention may be varied in many different ways within the scope of the invention. Thus the clamping surfaces 8 and 9, while extending in parallel with one another, may be curved instead of straight, as viewed in a section perpendicular to the mouth, for instance, so that such a section of the clamping surface 8 is concave while the corresponding section of the clamping surface 9 is correspondingly convex.

What I claim is:

20. 1. A manually-operable self-closing clamping device for closing a collapsible mouth of a flexible-walled container, comprising a substantially rigid frame having a through passage for receiving said container at the region of its mouth with the latter open, said frame having a clamping surface adapted to engage one side of the container mouth; a double-branched resilient clamping member having elongate branches connected by a yoke portion, said branches extending alongside each other; means engaging an end of one branch of said clamping member, mounting the latter on the frame, the two branches of said member extending substantially parallel to the through passage of the frame, the other branch of the clamping member extending beyond the extremity of the one branch, curving toward and extending to the clamping surface of the frame, said branches of the clamping member being biased toward each other whereby the curved portion of the said other branch is biased toward said frame clamping surface to collapse the mouth of the container thereagainst and seal the same; and opening cam means cooperable with said other branch of the clamping member to force the curved portion thereof away from the frame clamping surface in response to lateral movement of the yoke portion of the clamping member.
25. 2. The invention as defined in claim 1, in which the branches of the clamping member where they are co-extensive are substantially rectilinear and form between them a small acute angle.
30. 3. The invention as defined in claim 2, in which the opening cam means engages a rectilinear portion of the said other branch of the clamping member.
35. 4. The invention as defined in claim 3, in which the frame has a pair of spaced portions between which the clamping member extends, and in which the cam means comprises a bridge-like member disposed between and secured to said spaced portions of the frame and having a laterally-extending portion engaged with the said other branch of the clamping member.
40. 5. The invention as defined in claim 4, in which the bridge-like member of the cam means is disposed between the two branches of the clamping member.
45. 6. The invention as defined in claim 5, in which the said one branch of the clamping member has an opening, and in which the bridge-like member has a boss projecting through the said opening, said opening and boss constituting a part of the means mounting the one branch on the frame.
50. 7. The invention as defined in claim 6, in which the clamping member comprises a leaf spring, the branches of which are integral with each other.
55. 8. The invention as defined in claim 1, in which the frame comprises a pair of separate, mating members, each of said members having positioning means for engaging and positioning opposite wall portions of said container.
60. 9. The invention as defined in claim 8, in which the

mating members of the frame have cooperable and complementary interlocking means, and have cooperable clamping elements for clamping the said opposite wall portions of the container.

10. The invention as defined in claim 9, in which the interlocking means comprise projections and recesses on the frame members, said members in the regions of the projections and recesses being slightly resilient to enable them to be slightly deformed and snapped into engagement with one another.

11. The invention as defined in claim 10, in which the mating frame members comprise molded plastic pieces, each piece constituting a single unitary structure integral with the said interlocking means and the said clamping elements.

12. The invention as defined in claim 9, in which the cooperable clamping elements of the mating members have shallow recesses and round-faced projections adapted to engage the said opposite wall portions of the container.

13. The invention as defined in claim 8, in which one frame member carries the said clamping surface of the frame.

14. The invention as defined in claim 8, in which one of the mating members has two spaced portions, and in which the said opening cam means comprises a bridge member extending between and connecting said spaced portions.
